UNITED STATES PATENT OFFICE.

LUCIUS J. KNOWLES, OF WORCESTER, MASSACHUSETTS; HELEN C. KNOWLES, FRANCIS B. KNOWLES, AND HENRY A. MARSH, EXECUTORS OF SAID LUCIUS J. KNOWLES, DECEASED, ASSIGNEES TO FRANCIS B. KNOWLES, OF SAME PLACE.

SHUTTLE-BOX-OPERATING DEVICE FOR LOOMS.

SPECIFICATION forming part of Letters Patent No. 329,396, dated October 27, 1885.

Application filed July 16, 1881. Serial No. 37,985. (No model.)

To all whom it may concern:

Be it known that I, LUCIUS J. KNOWLES, of Worcester, in the county of Worcester and State of Massachusetts, have invented certain new and useful Improvements in Shuttle-Box-Operating Devices for Looms; and I do hereby declare that the following is a full, clear, and exact description of the same, reference being had to the accompanying drawings, forming a part of this specification, and in which—

Figure 1 represents a vertical section through a loom-frame just in front of the lathe and shuttle-boxes, showing a side view of said lathe and shuttle-boxes with my improvements applied thereto, as well as a side view of the arch-stand or upper part of the loom-frame, as will be hereinafter more fully described. Fig. 2 represents, upon an enlarged scale, a central vertical section through a portion of one of the shuttle-boxes and its lifter, taken on line *a*, Fig. 1, showing my improvements applied to the same; and Fig. 3 represents, upon the same enlarged scale as Fig. 2, a vertical section through a portion of the lathe and one of the shuttle-boxes, showing a side view of my improvements, the lifter-rod being shown by full lines attached to the shuttle-boxes and by dotted lines detached from the same, as will be hereinafter more fully described.

My invention consists in the combination of the shuttle-boxes and a lifter having laterally-projecting arms for supporting said shuttle-boxes with the lifter-rod, a flange formed upon or secured to the bottom of the shuttle-boxes provided with a horizontal opening, and a screw or stud fastened to the upper end of the lifter-rod upon a line with the opening in the aforesaid flange and adapted to be inserted into said opening, as and for the purpose hereinafter described.

To enable those skilled in the art to which my invention belongs to make and use the same, I will proceed to describe it more in detail.

In the drawings I have represented so much of an ordinary loom as is necessary to show

the nature and advantages of my improvements.

The parts marked *A* represent the frame-work of the loom; *B*, the lathe; *C*, the hand-rail; *D*, the lay-swords; *E*, the shuttle-boxes, which are arranged and operate upon the parts *F* of the lathe *B*; *G*, the shuttle-box lifters; *H*, the lifter-rods; *I*, the lifter-rod springs; *J*, the lifter-rod tubes; *K*, the rocker-irons, and *L* the protector-rod upon which the protection-fingers *L'* are secured for bearing upon the shuttle-binders *M*, and daggers *N* for stopping the loom when the shuttles are in any way retarded or stopped during the operation of weaving. The shuttle-box lifters *G* are raised and lowered with the lifter-rods *H* by means of the drop-box levers of the loom, said levers being connected with the tubes *J* upon the lifter-rods by means of connecting-rods *b* and chains *c*. The latter work on wheels or trucks *d*, supported by the frame-work of the loom. If desired, a better understanding of the operation of said drop-box levers may be obtained by reference to the Patent No. 134,992, granted to me January 21, 1873, for improvements in looms. The bottoms of the shuttle-boxes rest upon the outer ends of the lifter-arms *g*, formed upon or secured to the lifters *G*, which latter are in turn formed upon or secured to the upper ends of the lifter-rods *H*. Therefore, when said lifter-rods and lifters *G* are raised by the drop-box levers, as aforesaid, the shuttle-boxes are also raised, and when the lifter-rods and lifters are lowered said shuttle-boxes follow, owing to their weight and to their being attached to the upper ends of the lifter-rods, as hereinafter described. The shuttle-boxes are arranged to slide up and down in suitable ways, *h*, made in the parts *F* of the lathe. They are attached to the upper ends of the lifter-rods, as before stated, in the following manner: Upon the bottom of each shuttle-box, at or near its center, is formed or secured a flange, *e*, having a horizontal opening through the same, into which may be inserted a screw or stud, *f*, fastened in the upper end of each lifter-rod *H*.

upon a line with said opening. Said screws or studs are fitted loosely in said openings, and made of just sufficient length to extend through the flanges *e*, as shown in Figs 2 and 5 3 of the drawings.

By employing a fastening such as above described for attaching the shuttle-boxes to the lifter-rods I am enabled to remove said shuttle-boxes, when required for renewal, repairing, 10 or wiping the same, in a very convenient and expeditious manner by simply springing back the lifter-rods and parts attached thereto, as shown by dotted lines in Fig. 3, so as to withdraw the screws or studs *f* from the openings 15 in the flanges *e*, when the shuttle-boxes may then be easily taken out. In performing said operation the attendant in practice, while springing back the parts, as before described, with one hand, removes the shuttle-box with 20 the other. As the lifter-rods are of considerable length, and held (when detached from the shuttle-boxes) only at their lower ends, they may be easily sprung at their upper ends to obtain the result above described. The 25 openings in the bottoms of the parts *F* of the lathe through which they pass are also made of sufficient size to admit of said springing motion.

It will be understood that when the lifter-rods are in their normal positions with the

35 screws or studs *f* in the openings *e*, as shown by full lines in the drawings, they are held with sufficient firmness and rigidity to securely hold the parts together, and cannot become disengaged, except by springing the lifter-rods back by force, as before described. Therefore it will be seen that my improved fastening, while admitting of the easy removal of the shuttle-boxes, also holds said shuttle-boxes in a secure manner against a rocking or wabbling 40 motion, owing to the construction before described, and may be operated up and down with as little friction as when rigidly or otherwise fastened to the lifter-rod.

The other portions of the loom shown in the 45 drawings, being of old and well-known construction, require no further description.

Having described my improvements in shuttle-box-operating devices for looms, what I claim therein as new and of my invention, 50 and desire to secure by Letters Patent, is—

The combination, with the shuttle-boxes *E* and lifter *G*, having arms *g*, of lifter-rod *H*, pin *f*, and flange *e*, substantially as shown and described, for the purpose stated.

LUCIUS J. KNOWLES.
